UNITED STATES PATENT OFFICE.

SAMUEL D. HACKMAN, OF BURROAK, MICHIGAN.

BUILDING-BLOCK.

SPECIFICATION forming part of Letters Patent No. 764,459, dated July 5, 1904.

Application filed October 31, 1902. Serial No. 129,593. (No model.)

To all whom it may concern:

Be it known that I, SAMUEL D. HACKMAN, a citizen of the United States, residing at Burr-oak, in the county of St. Joseph and State of 5 Michigan, have invented a new and useful Building-Block, of which the following is a specification.

This invention relates to bonding or inter-fitting building blocks or bricks which may 10 be employed for ordinary building purposes or which may be constructed of special mate-rials or compounds for special purposes; and one object of the invention is to produce a building-block in which the building-cement 15 will be entirely concealed and the blocks so united as to be mutually supported and pre-vented from lateral movement.

The invention consists in the construction and novel combination and arrangement of 20 parts hereinafter fully described, illustrated in the accompanying drawings, and pointed out in the claim hereto appended.

In the drawings illustrative of the invention, Figure 1 is a perspective view of one of 25 the improved building blocks or bricks de-tached. Fig. 2 is a transverse section of a plurality of the bricks or blocks assem-bled. Fig. 3 is a perspective view of one of the building-blocks as it will be constructed for 30 building the corners of walls or other struc-tures. Fig. 4 is a perspective view of one of the improved building-blocks in curved shape as they will be employed in building arches or domes.

35 The improved building-block will prefer-ably be constructed of Portland cement or other similar waterproof material or com-pound, so that when the structure is erected it will be waterproof and will be found very 40 efficacious in building dams, cisterns, tanks, silos, area-walls, and other structures exposed to dampness and moisture.

The building-blocks will be formed with 45 longitudinal grooves upon their straight flat edges and preferably, also, upon their ends with the material of the blocks depressed ad-jacent to the tongue to provide cavities for the binding-cement, so that when the blocks are assem-bled the cement will be entirely con-50 cealed between the courses, and therefore not

exposed upon the sides of the structure errect-ed with the blocks.

The blocks may be constructed of any re-quired size and shape, but will preferably be of about the ordinary size of common build-ing-brick, and I do not, therefore, wish to be 55 limited in any manner to the shape or sizes of the blocks.

For the purpose of illustration a number of the building-blocks of different shapes and 60 sizes are shown, Fig. 1 representing an ordi-nary brick form, Fig. 3 a corner-block, and Fig. 4 a block suitable for use in building arches, domes, and similar structures.

The body of the block is indicated at 10, the 65 groove at 11, and the tongue at 12, the grooves of each block being located upon the opposite side of the block from the tongue and defin-ing flat bearing-faces of a width greater than the width of the grooves, as clearly shown in 70 Fig. 2 of the drawings. Preferably the tongues and grooves will be arranged upon all the edges of each block, as shown in Figs. 1, 3, and 4, wherein the groove 11 is shown upon one edge and likewise continued upon one 75 end of each block, and the tongue 12 likewise located upon the opposite edge and continued upon the opposite end from the groove, so that when the blocks are assem-bled as indi-cated in Fig. 2 the two tongues and grooves 80 interfit, as will be obvious. The improved form of block is capable of erection into a wall with the joints "breaking" in the ordinary manner; but as the manner of assem-bling the blocks into a wall is so well understood this 85 feature is not illustrated. Longitudinally dis-posed in the material of the block adjacent to the tongues are cavities 13, preferably in-clined inwardly and downwardly from the faces of the block toward the roots of the 90 tongues, forming a concaved upper edge with the rib 12 longitudinally disposed in the cen-ter thereof, so that when the blocks are as-sem-bled as in Fig. 2 angular-shaped closed and concealed cavities will be formed between 95 the meeting edges and entirely below the flat edge of the adjacent block. As shown, these cavities are designed to be filled with the bind-ing-cement 14, which will likewise preferably be of Portland or other similar suitable mate-100

rial or compound. The sides of the tongues and grooves will preferably correspond in size, so that when the blocks are assembled they will closely engage and effectually prevent 5 relative lateral movement. By this arrangement it will be obvious that an ample supply of cement may be placed between the adjacent surfaces of the blocks to securely "bind" them, while at the same time the outer edges 10 of the blocks may be in direct contact, as shown in Fig. 2, thereby entirely concealing the cement within the joint, exposing a greater surface of the adjacent block to the action of the binding material, and preventing its exposure 15 to the moisture upon the outer surface of the wall or other structure. This is a very important feature of the invention and adds materially to the value of the structure when erected, as the binding-cement is thereby protected 20 from the outside moisture and deterioration from that cause effectually prevented.

The form of block which will be employed at the corners of the structures is shown in Fig. 3 consisting in two blocks, preferably of 25 unequal lengths, united at right angles and constructed "rights" and "lefts." so that when built into the walls the requisite breaking of the joints will be accomplished. This form of corner-block is therefore a very important 30 feature of the invention and greatly increases the efficiency and value of the device and likewise materially increases the strength of a structure embodying the same.

The blocks may be constructed of any suitable material, such as waterproof or Portland 35 cement or its compounds and similar compounds or material or of ordinary brick-clay, fire-clay, terra - cotta, or other material or compounds and provided with the reversely-disposed tongues and grooves, together with 40 the binding-cement cavities 13, and I there-

fore claim the right to the use of the special form of building - block herein illustrated when constructed of any of the various materials usually employed for building blocks 45 or bricks. I also claim a special advantage in forming a building-block with one portion at right angles to the other portion, as shown in Fig. 3, blocks of this form to be employed in the building of the corners of the structure. Blocks thus constructed will very greatly stiffen and strengthen the structures at the corners, enabling them to resist a much greater strain than structures erected with the ordinary forms of building-blocks or of 50 building-blocks of the bonding or interfitting form joined at the corners in the ordinary manner.

Having thus described the invention, what is claimed is—

A building-block comprising a body portion having its upper edge and one end wall thereof concaved and provided with a centrally-disposed locking-rib having converging side faces, the lower edge of said block 65 and the opposite end wall thereof being provided with correspondingly-shaped seating-grooves defining flat bearing-faces of a width greater than that of the grooves, the locking-rib of one block being adapted to exactly fit 70 the seating-groove of the mating block with the flat bearing-face of the mating block extending entirely across the concavity of the opposite block to thereby prevent lateral displacement of said blocks.

In testimony that I claim the foregoing as my own I have hereto affixed my signature in the presence of two witnesses.

SAMUEL D. HACKMAN.
